UNITED STATES PATENT OFFICE.

WALTER ALLEN STEWART, OF SMITH'S FALLS, ONTARIO, CANADA, ASSIGNOR TO
SMITH'S FALLS MALLEABLE CASTINGS COMPANY, LIMITED, OF SMITH'S
FALLS, ONTARIO, CANADA, A JOINT-STOCK COMPANY OF ONTARIO.

DEVICE FOR PREVENTING THE CREEPING OF RAILWAY-RAILS.

1,303,515.

Specification of Letters Patent. Patented May 13, 1919.

Application filed February 10, 1919. Serial No. 276,093.

To all whom it may concern:

Be it known that I, WALTER ALLEN STEWART, of the town of Smith's Falls, in the county of Lanark, in the Province of Ontario, Canada, have invented certain new and useful Improvements in Devices for Preventing the Creeping of Railway-Rails, of which the following is the specification.

My invention relates to improvements in devices for preventing the creeping of railway rails and the object of the invention is to devise a simple device which may be readily and quickly placed in position in engagement with the rail so as to absolutely prevent it creeping longitudinally and it consists essentially of the following arrangement and construction of parts as herein-after more particularly explained.

Figure 1, is a perspective view of my device showing it applied to a portion of a railway rail and a portion of the sleeper supporting the rail.

Fig. 2, is a longitudinal section through Fig. 1.

Fig. 3, is a cross section on line $x-y$, Fig. 2.

Fig. 4, is a plan section through the central portion of my device taken on line $x'-y'$ Fig. 3.

In the drawings like characters of reference indicate corresponding parts in the various figures.

1 indicates a portion of a railway rail provided with the usual base flange 1^x. 2 indicates a portion of the sleeper upon which the rail is carried and to which it is secured. 3 indicates the main portion of my device which forms a holder, the main portion of which is formed by two parallel members 3^x and 3° connected together by cross bridging portions 3¹, 3² and 3³. One end of the portion 3 is formed into a hook 3⁴ adapted to engage the edge portion 1° of the rail flange 1^x, the parallel portions 3^x and 3° being connected together at this end by the hook portion 3⁴. The opposite end of the portion 3 is inclined downwardly at 3⁵, the extreme end being increased in depth where the side portions 3^x and 3° are connected together by the bridging portion 3³. By this means this end of the portion 3 is reinforced for a purpose which will hereinafter appear.

The ends of the portions 3^x and 3° where

they are connected together by the bridge 3³ are extended upwardly in hook form at 3⁶, 55 the hook portions 3⁶ being webbed together at 3⁷ so as to form a key receiving orifice 3⁸. At the upper end of the hook portion 3⁶ a hook extension 3⁹ is formed, such hook portions being connected together by the extension of the web 3⁷. In the center of the portions 3^x and 3° are recesses 3¹⁰ and 3¹¹ extending into the upper edge of such portions 3^x and 3°. The bottom of each of the recesses 3¹⁰ and 3¹¹ at the end of each recess 60 adjacent to the hook portion 3⁶ is downwardly inclined to conform with the incline of the portion 3⁵. From the outer face of the portion 3^x extends a tongue 3¹² for a purpose which will hereinafter appear. 70

4 indicates a bracket provided with a vertical portion 4^x adapted to bear against the vertical face of the sleeper 2 and a horizontal portion 4° which extends through the recesses 3¹⁰ and 3¹¹. The vertical portion 75 4^x of the bracket 4 is provided with a vertical slot 4¹, the outer vertical edges of which are flared outwardly as clearly shown in Fig. 4. The tongue 3¹² extending from the portion 3 passes through the major portion of 80 the slot 4¹, the outer extremity of the tongue being riveted out or spread into the flared portion of the slot so as to prevent its withdrawal. The vertical width of the tongue 3¹² is less than the length of the vertical slot 85 4¹ and, therefore, allows of a relatively vertical movement between the bracket 4 and the holder 3. The upper face of the horizontal portion 4° is provided with a rectangular recess 4² in which fits a hardened metal plate 90 5 provided on its upper face with a plurality of triangular ribs 5^x so as to form a gripping surface. The hardened plate 5 is held within the recess 4² by having small portions 4³ in the side edges of the recess swaged over 95 so as to extend over the edge of the hardened plate 5.

6 indicates a tapered key which passes through the key receiving orifice 3⁸ and longitudinally between the portions 3^x and 3° of the holder 3, the lower edge of the key bearing upon the bridging portions 3² and 3³ and the upper edge of the key bearing against the lower face of the horizontal portion 4° of the bracket 4. 100

When it is desired to place my device in

position so as to secure the rail all that it is necessary to do is to move sufficient gravel from under the rail adjacent to the rail sleeper, then insert the holder 3 beneath the rail so that the edge 1' of the flange 1^x of the rail enters into the hook portions 3⁶, the holder 3 then being in an inclined position relative to the rail or with the portions 3⁵ parallel with the lower face of the rail. The 10 opposite end of the holder is then lifted up so that the hook 3⁴ is brought into a position to engage with the edge 1⁰ of the flange 1^x. The holder is then moved crosswise of the rail so that the flange edge 1⁰ enters the hook 15 3⁴ and the flange edge 1' into the hook 3⁴. The key 6 is then inserted into the holder by passing through the orifice 3⁸ and between the horizontal portion 4⁰ of the bracket 4 and the bridging portions 3² and 3'. When 20 the device is in this position the vertical portion 4^x of the bracket 4 bears against the adjacent vertical face of the sleeper 2 and is thereby held from longitudinal movement in relation to the rail in one direction. When 25 in this position the key 6 is driven, forcing the bracket 4 upwardly and the gripping surface of the upper face of the bracket into engagement with the lower face of the rail flange 1^x. By this means the rail is held 30 definitely in place from longitudinal movement in one direction. A similar device may be placed on the opposite side of the sleeper and engaging the rail so as to prevent longitudinal movement of the rail in the opposite 35 direction.

My device is preferably made of malleable iron with the exception of the inserted plate 5, which necessarily must be of hard metal in order to form a gripping surface engaging 40 the rail flange. It will be readily seen that my device forms a positive means for preventing the rail creeping and when once applied will never crack or jar loose owing to the use of the malleable iron key which, 45 when driven into place, forces up the hardened metal portion against the bottom of the steel rail, the hooked ends of the holder by the same operation being forced into engagement with the edges of the rail flange.

50 To remove the device all that it is necessary to do is to drive out the key and the device may be readily removed from the rail.

What I claim as my invention is.

1. In a device for preventing the creeping 55 of railway rails, a holder member having a key receiving channel extending longitudinally therethrough and having hook members at each end adapted to engage the edges

of the base flange of a rail, a movable member adapted to be inserted between the base flange of the rail and the holder between the hook portions thereof, and a key adapted to be driven longitudinally through the holder against the lower face of the movable member, and a rail gripping member carried by 65 such movable member.

2. In a device for preventing the creeping of railway rails, a holder member having a longitudinal passageway therethrough for the passage of a key and having the upper face inclined downwardly toward one end, a hook portion at each end of the holder and a supplemental hook portion extending inwardly from the hook portion at the end of the inclined portion of the holder, a movable member comprising a vertical portion adapted to bear against the vertical face of a sleeper and a horizontal portion adapted to extend between the base of the rail and the holder and having its upper face formed with a rail gripping surface, and a key adapted to extend longitudinally through the holder beneath the horizontal portion of such member so as to force it into engagement with the rail. 85

3. In a device for preventing the creeping of railway rails, a holder adapted to engage the base flange of a rail, a projection extending outwardly from one face of the holder, a movable member extending between the holder and the lower face of the base flange of the rail and having a vertical slot into which the projection extends and is riveted to have free vertical movement within the slot, such movable member being adapted to bear against the rail supporting sleeper and having its upper face formed with a gripping surface, and means extending into the holder between the holder and the movable member for forcing such movable member 90 into contact with the rail. 95

4. In a device for preventing the creeping of railway rails, a holder adapted to engage the base flange of a rail, a movable member extending between the holder and the lower face of the base flange of the rail and adapted to bear against the rail supporting means and to engage the lower face of the rail, and means extending into the holder between the holder and movable member for forcing such 105 member into the engaged position with the rail. 110
